ORTHOPEDIC BRACE AND ARCH SUPPORT

Filed April 14, 1924

2 Sheets-Sheet 2

Inventor:
William Jones

By
A. S. Bailey Attorney.

UNITED STATES PATENT OFFICE.

WILLIAM JONES, OF DENVER, COLORADO.

ORTHOPEDIC BRACE AND ARCH SUPPORT.

Application filed April 14, 1924. Serial No. 706,460.

To all whom it may concern:

Be it known that I, WILLIAM JONES, a citizen of the United States of America, residing at the city and county of Denver and State of Colorado, have invented new and useful Orthopedic Braces and Arch Supporters, of which the following is a specification.

My invention relates to a new orthopedic brace and arch support for weak and broken-down arches.

And the objects of my invention are:—

First: To provide an arch-supporting brace that is arranged and adapted to fit the longitudinal arch only and that will gradually straighten the longitudinal arch portions and the heel portions of the feet that have grown out of alignment into their natural and normal alignment positions relating to each other, by the application of adjustable pressures on the outside of the heel against the inside longitudinal arch portion of each foot; and also to provide a brace that will extend from the longitudinal arches to the transverse arches and that will also at the same time provide an adjustable brace for both the longitudinal and the transverse arches of the feet.

Second: To provide a simple, inexpensive and adjustable pressure-exerting orthopedic brace that will rectify the disalignment of any bones in the feet that have worked out of their original normal position, and that will strengthen and cure weak and broken arches by the application of transverse obliquely applied, gradually increasing pressures from the outside of the heels to the inside longitudinal arches of the feet, and also to the transverse arches of the feet.

I attain these objects by the mechanism illustrated in the accompanying drawings in which:—

Figure 1 is a side view of the improved arch supporter as it appears when secured upon the foot, the same being adapted for supporting the longitudinal arch.

Figure 2 is a view similar to Figure 1, but showing a supporter adapted both for the longitudinal and transverse arches.

Figure 2^a is a perspective view of the supporter shown in Figure 2.

Figure 3 is a bottom view of Figure 1.

Figure 4 is a bottom view of Figure 2.

Figure 5 is a side view looking at the opposite side of the supporter shown in Figure 1.

Figure 6 is a side view looking at the opposite side of the supporter shown in Figure 2.

Figure 7 is a side view of a longitudinal arch supporter applied to a foot, and of a slightly different construction from the supporter shown in 1, 3 and 5.

Figure 8 is a bottom view of Figure 7, and

Figure 9 is a view looking at the opposite side of the supporter to that shown in Figure 7.

Similar letters of reference refer to similar parts throughout the several views.

Referring to the drawings:—

The numeral 1 designates a human foot; and the numeral 2 designates an arch-supporting brace embodying my invention.

My arch-supporting brace fits around the heel 3 of the foot 1, and it is made in numerous sizes and shapes.

My combined heel and arch brace shown in Figure 1 is for application to feet that require a brace that fits the heel 3 and the longitudinal arch 4 of the foot, and the combined heel and arch brace shown in Figure 2 is longer than the brace shown in Figure 1 and is adapted to fit the longitudinal arch 4 and the transverse arch 5 of the foot.

My combined heel-fitting and arch-supporting brace is made of any suitable thin and strong and integrally resilient metal that will retain the shapes it is formed into to fit the feet accurately.

My heel-fitting arch-supporting brace is especially designed to relieve the pain of weak and also of broken-down arches; and will in time cause them to reassume their original arch form free from pain and permanently cured.

My invention effects the cure of weak and broken-down arches by removing the cause of them, which is, that the bone in the heel of the foot gradually moves to one side of its original straight alignment with the longitudinal arch bones of the foot, and consequently if the heel of the foot can be moved

or be caused to move back into its natural alignment position the pain will cease and the will regain its strength and its natural curved shape; and my heel and arch-supporting brace is made and constructed in the following manner to effect these results:—

- A thin plate of any resiliently springing metal, preferably German silver, is made in the shape of Figures 2 and 6, the heel end 5^a 10 of which may vary from about an inch to an inch and three-quarters wide at the point 6, and from this point may taper smaller to its end to from about three-quarters of an inch to about an inch at 7 and then taper 15 smaller to a rounded end at 8; and this heel end is adapted to rest squarely upon the corresponding part of the shoe.
- In Figure 5 this end 8 is provided with a slot 9 that is made wide enough to receive 20 a strap 10, which may be non-elastic or elastic as desired, and its upper side edge is provided with two depending pointed teeth 11, which may be formed integral with the metal of the heel band 5^a at its end 8 or 25 these teeth may be formed on another piece of metal 12 and the piece of metal 12 be secured to the upper edge of the end 8 of the heel band by rivets or solder or other means.
- 30 A strap 10 is secured at its outer end to the central portion 14 of the width of the longitudinal arch portion 15 of the brace, and this strap 10 is made long enough to be grasped by the hand and be guided side- 35 wise into the slot 9 and be pulled up against the teeth hard enough to force them to penetrate the strap and thus lock the strap to the curved heel member of the brace, the effect sought being to pull on the strap and 40 thus draw the free end of the heel member and the upwardly curved flange portion 16 of the longitudinal arch-fitting portion 15 together against the outside of the heel and the inside of the almost vertical portion of 45 the top of the longitudinal arch along the length of the top portion of the curve of the brace together tightly enough to draw them and their bones into alignment, and to hold them in alignment and then lock the strap 50 to the teeth of the slot 9 of the free end of the heel band 5^a.

The brace shown in Figures 1, 3 and 5 is made of a resilient metal plate and is covered with leather inside and out, but the brace 55 shown in Figures 2, 4 and 6 is without any covering; and all of the different sizes and shapes of braces can be used without coverings or they can be covered with any suitable covering material.

- 60 The short brace shown in Figures 1, 3 and 5 is made to extend to cover the longitudinal arch portion of the feet only; but the brace shown in Figures 2, 4 and 6 is made to extend to and cover the transverse arch of the 65 feet, as well as the longitudinal arch of the

feet; and the free end 8 of its heel band 5^a is provided with a buckle 18 that is secured to it within its edge, preferably, so that it will not hurt the feet; and the free end of its strap 10 fits easily in the buckle and is 70 provided with a buckle pin 19, receiving holes 20 placed quite close together to enable the strap to be drawn to varying degrees of pulling strains and fastened where desired.

The transverse arch-fitting end of my 75 brace is provided with a raised, round, upwardly curved surface 21 that slopes up from the extreme end of the opposite sides of the extreme end portion of the brace; which upwardly rounded, concaved portion 80 is formed by pressing a convex recess into the under side of the plate, and the upper surface of this concaved portion of this transverse arch-fitting portion of my brace fits up into the center of the transverse arch, 85 and its edges bear all around against the inside of the shoe.

From the inner side at a point 22 from the extreme end of the brace the longitudinal part of my brace commences to curve upwardly to a point 23 from which it curves downwardly to the point 24 which is the point where the heel band commences to curve into the heel surrounding member of my brace, while the inside upwardly curved 90 side of my brace curves up gradually from the inner edge 25 of the brace to a nearly vertically positioned edge 26 that extends along the length of the inside of the foot, and from the point 26 it curves sharply 95 downward into the transverse arch portion at 21 to points 28, from which points 28 the outer edges of the transverse arch part of the brace rest on the shoe.

In Figures 7, 8, and 9, I have shown a 100 supporter for longitudinal arches, which is of a slightly different construction from the supporter shown in Figures 1, 3, and 5.

This supporter comprises a resilient sheet metal brace 29, which is adapted to bear 110 against and conform to the inner side of the foot and extend under the longitudinal arch. This brace merges into a narrow semi-circular portion 30, which extends around the heel, and terminates in a straight forwardly 115 extending portion 31 which lies alongside the heel, and is provided at its end with a short upwardly projecting tongue 32. The heel portion 30, is adapted to rest upon the corresponding portion of the shoe, and 120 against the counter, or that part of the shoe which surrounds the heel, and therefore, does not engage the heel in such a manner as to rub or irritate the same.

While this brace may be used without a 125 covering, I preferably encase that portion of it which bears against the side and under portion of the foot, in a pocket piece 33, comprising a leather strip of the size and shape of this part of the brace, which is stitched 130

around its upper, forward, and under edges, to a leather strap 34, which is long enough to extend under the foot and up against the opposite side of the foot to a height substantially equal to the part 29 of the brace.

The strap 34 is of sufficient width, where it extends under the arch, to insure comfort to the wearer, and the free end portion 35 which lies against the outside of the foot is 10 of a progressively diminishing width, as shown in Figure 9. A pocket piece 36 is stitched along its bottom, forward, and top edges to the part 35 of the strap, and this pocket piece is provided with a number of 15 eyelets 37, a pocket being provided between the piece 36, and the end 35 of the strap to which it is secured, said pocket being open at its rear end. The pocket formed by the piece 33 and strap 34 is also open at its rear 20 end; and the arch-supporting part 29 of the brace is inserted in this pocket, while the end 31 of the heel portion 30 is adapted to be inserted in the pocket formed by the piece 36 and the end 35 of the strap 34. The end 25 portion 31 of the brace is inserted in this latter pocket, and the tongue 32 on this end portion is passed through one of the eyelets 37, thus holding the brace in arch-supporting position.

While I have thus described the general outline and also illustrated the two principal kinds of braces—one for the longitudinal arch and the transverse arches—it must be borne in mind that every brace must be 30 curved in all of its parts and throughout its length and width to fit exactly the foot that is to wear it.

The operation is as follows:—

Having fitted a brace to a foot, the operator or the wearer takes the strap in one 40 hand and puts it in the toothed slot or in the buckle, whichever securing device has been placed on the free end of the heel band, and pulls or draws the free end of 45 of the heel band and the longitudinal arch member of the brace together to clamp them against the opposite sides of the foot, which action exerts a pressure on the outside of the heel that tends to move it inwardly, and 50 at the same time exerts a pressure on the longitudinal arch portion of the brace through the bearing of the vertically inclined upper edge portion of this arch member on the inside rounded or curved portion 55 of the inside of the foot, which tends to move it outwardly and thus between these two opposite direction pressures brings the bone of the heel and bones of the longitudinal arch into their natural position of alignment with each other.

The pressure should be applied gradually where the brace is applied to feet that are painfully sore, and the braces should be worn all of the time, and should be tightened and the side pressure gradually in-

creased from time to time until the pain disappears and a complete cure has been effected of the weak or fallen arch.

Having described my invention, what I claim as new and desire to secure by Letters Patent, is:—

1. An orthopedic brace and support comprising a resilient plate curved to fit and support the arch portions of the foot and provided with a heel surrounding band portion extending from its inner side and having a free end; a strap secured at one end to the arch-supporting member of said brace; and a device secured to the free end of said heel band for receiving the said strap and securing it in such tightened-up positions as will clamp the free end of the heel band and the vertically inclined part of the arch-supporting part of the brace against the opposite sides of the foot. 75

2. In an arch and heel rectifying and supporting brace for weak and broken-down arches the combination of a resilient plate consisting of a plate portion adapted to fit the bottom of the feet and having an integral portion extending from the curved longitudinal part of the plate that fits the longitudinal arch of the foot extending around and fitting around the heel of the foot and having a free end provided with a strap-securing device; a strap secured to the central portion of the arch and adapted to be drawn through said strap-securing device and tightened to draw the outside of the heel and the inside of the round arch of the plate to clamp the heel of the foot and the arch of the foot to move them in opposite directions from and also toward each other to rectify their disalignment to each other. 90

3. In a brace and arch support of the character described, a resilient metal plate, comprising a portion shaped to fit under the longitudinal arch, and against the inner side of the foot, and a portion which extends therefrom around the heel and terminates; fastening means on the terminal end of the heel portion, and a strap extending from the arch supporting portion and passing beneath the foot, its free end being secured by said fastening means. 105

4. In an arch support of the character described, a resilient metal plate comprising a portion shaped to fit under the longitudinal and transverse arches, and against the inner side of the foot, and a portion extending therefrom around the heel and terminating; fastening means on the terminal end of the heel portion, a strap extending beneath the foot and connecting the arch supporting portion and the said securing means, said supporter tending to press the heel bone inward and raise the longitudinal arch. 110

5. The combination of an arch and free- 125

ended heel-fitting plate with a strap secured to the arch portion of the plate; a slot in the free end of the heel portion; and teeth depending from the upper side of said slot and arranged to penetrate said strap and hold it when the strap is pulled through said slot and tightened to clamp the heel and the arch portions of the plate against the opposite sides of the foot, and then

force the strap up against the teeth in said slot.

In testimony whereof I affix my signature in the presence of two witnesses.

WILLIAM JONES.
